UNITED STATES PATENT OFFICE.

MICHAEL BURNS, OF PHILADELPHIA, PENNSYLVANIA.

TREE-PROTECTOR.

SPECIFICATION forming part of Letters Patent No. 539,344, dated May 14, 1895.

Application filed September 18, 1894. Serial No. 523,344. (No model.)

To all whom it may concern:

Be it known that I, MICHAEL BURNS, a citizen of the United States, residing at Philadelphia, in the county of Philadelphia and 5 State of Pennsylvania, have invented certain new and useful Improvements in Tree-Protectors, of which the following is a specification.

The invention relates to tree protectors.

The object is to produce a simple and inexpensive device, in the nature of a guard, adjustable to trunks of trees varying in size, it being applied in a manner, to form a barrier and render the passage of caterpillars, or other pests, impossible.

With this object in view, the invention consists in a protector, comprising a body of pliable sheet metal, gauze, or like material, bent up into an approximately cylindrical form, and having its adjoining edges lapped and 15 detachably connected, whereby the diameter may be increased or decreased in a ready and convenient manner, and a spring or pliable wire fastening collar, encircling and interlaced at the upper end of the body, by 20 which it may be drawn well in, around the tree, the lower end being thereby spread or flared, and having its edge serrated or otherwise roughened; furthermore, in a protector, comprising a body of pliable sheet metal, 25 gauze or like material, bent up into an approximately cylindrical form, and having its adjoining edges lapped and detachably connected, whereby the diameter may be increased or decreased in a ready and convenient manner, and a spring or pliable wire fastening collar, encircling and interlaced at the upper end of the body, by which it may be drawn well in, around the tree, the lower end being thereby spread or flared, and having 30 its edge serrated or otherwise roughened and turned upward, within the body, to form a catch trough for the insects; and finally, in 35 details of construction.

The invention is illustrated in the accompanying drawings, forming part of this specification, in which like letters of reference indicate corresponding parts in the several views.

Figure 1 is a view in elevation of one embodiment of the invention applied, showing the wire-gauze body at its upper end drawn well in around the trunk of the tree and the

lower edge out of contact therewith by being flared, and the wire lacing by which the edges of the body are detachably connected. Fig. 55 2 is a view in central vertical section of a modified form of protector applied, showing the lower flared end thereof turned upward within the body as a catch-trough and the edge thereof out of contact with the trunk of the 60 tree.

In the drawings, A, represents the protector, preferably of wire gauze, approximately cylindrical and tapering toward the upper end. The body portion may, if desired, be 65 formed from sheet material, cut in a manner, so as to afford, when bent up, surplus lapping at the adjoining edges and thereby render the diameter adjustable to tree trunks varying in size. The edges are connected by 70 any suitable fastener, such as a wire lacing a, which may be continued in the form of an encircling collar at the upper end of the body, by being interlaced around, adjacent the edge, a tight joint being necessary at that point. 75 It may be at times found convenient to substitute for the pliable wire lacing around the upper edge of the body, a spring metal collar, for facility in applying the device. In forming the lapped seam, an increased diameter 80 is given the lower end of the body, so that the greater portion of its length will be held out of contact with the tree trunk, the lower edge being left rough, and by reason of the projecting ends of the longitudinal wires of 85 the gauze, passage thereover of insects, such as caterpillars, will be impossible.

In Fig. 2, of the drawings, the lower edge is shown, bent upward within the body, to serve as a catch trough a² in collecting the insects, 90 which may be readily destroyed by fire, upon removing the protector, and without injury to the device itself.

The many advantages of this device will be at once apparent from the foregoing description. Its extreme simplicity of construction, as well as the low cost of the manufacture, gives it a superiority over many of the devices now in use; again, its neat design, and the expeditious and convenient manner in 95 which it may be applied, together with its strength and durability, serve to make it useful, ornamental and effective in operation.

Having fully described the invention, what

I claim as new, and desire to secure by Letters Patent, is—

A tree protector comprising a body formed of wire gauze by being bent approximately 5 cylindrical and having its adjoining edges lapped and detachably secured, whereby the diameter may be adjusted, a spring wire fastening collar encircling the upper end of the body, the lower end thereof being flared and 10 turned upward within the body to form a

catch trough, with the ends of the longitudinal wires forming a rough edge, as specified.

In testimony whereof I have affixed my signature in the presence of two subscribing witnesses.

MICHAEL BURNS.
